UNITED STATES PATENT OFFICE.

DANIEL E. STAIR, OF ELKHART, INDIANA.

RECLAIMING BUCKET.

Application filed August 17, 1922. Serial No. 582,482.

To all whom it may concern:

Be it known that I, DANIEL E. STAIR, a citizen of the United States, residing at Elkhart, in the county of Elkhart and State of Indiana, have invented certain new and useful Improvements in Reclaiming Buckets, of which the following is a specification.

This invention relates to a new and improved clam-shell bucket, and more particularly to a bucket of this type adapted to operate with small head room and to ride easily in the bight of a line.

Various types of reclaiming buckets comprising numerous forms of clam-shell buckets are now in use in connection with conveying systems. A number of these buckets require additional lines for latching and unlatching the buckets. In many types of buckets in which the fall lines are expected to operate in closing the buckets, the fall line is so reeved through sheaves in the bucket that when the bucket is moved by the traction cable, this reeving interposes considerable frictional resistance. Use of the additional bucket operating lines also unduly complicates the conveying system.

It is an object of the present invention to provide a bucket which is adapted to operate with but little head room and to ride easily in the bight of the line, and in which the fall cable is reeved through sheaves in such manner as to obtain ample leverage while the bucket is digging or closing.

It is a further object to provide a bucket in which the reeving is eliminated when the bucket is fully opened or fully closed so that it may be moved along the conveyor with a minimum of frictional resistance.

It is also an object to provide a bucket in which the opening and closing are accomplished without additional latch or other cables.

Other and further objects will appear as the description proceeds.

Broadly, my invention comprises a clam-shell bucket consisting of a pair of coating bucket members hingedly connected together. A lever arm is connected to each bucket member and means are attached to these arms adapted to detachably engage the bucket above its center of gravity. When supported from these means, the bucket is closed by gravity. These means are so related to the portion of the bucket which they engage that when in the closed position, upon the weight of the bucket being re-

moved from the means, they move out of engagement with the bucket and permit it to be opened by gravity. Sheaves are carried by the lever arms upon which the fall rope is adapted to pass.

In the preferable form, an additional sheave is located intermediate the two first-mentioned sheaves and is supported by arms from the bucket. This additional sheave aids in the functioning of the lever arms in the closing operation.

I have illustrated a preferred embodiment of my invention in the accompanying drawings, in which—

Figure 1 is a view of the bucket in the closed position;

Figure 2 is a view of the bucket in the open, discharging, tractioning position; and

Figure 3 is a view of the bucket in the opened and digging position.

The bucket comprises the two halves 6 and 7 which are of ordinary clam-shell design. These buckets are hingedly connected together at the hinge member 8. The adjacent upper edge portions of the bucket are provided with stops 9 and 10 adapted to prevent the bucket from opening wider than the position shown in Figure 2. The sheave 11 is supported from the two bucket members by means of supporting arms 12 and 13. The lever arms 14 and 15 are pivotally connected to the two bucket halves, and these arms, adjacent their outer ends, carry the sheaves 16 and 17 respectively and are provided with the abutting stops 18 and 19. The dogs 20 and 21 are pivotally hung from the two lever arms as best shown in Figure 2. These dogs are provided with the hook portions 22 and 23 adapted to engage the pivot member 8. The fall rope 24 is passed under the sheaves 16 and 17 and passes over the sheave 11.

When the bucket is in the position as shown in Figure 2, it is open and is adapted for tractioning. The fall rope passes smoothly under the upper sheaves 16 and 17 and above the lower sheave 11 as the bucket is moved along the conveyor. When the bucket reaches the desired loading point, the fall rope is payed out until the bucket rests upon the material to be reclaimed. The fall rope is then further payed out and the lever arms 14 and 15 are swung by gravity to the position of Figure 3. The inner lower surfaces of the dogs 20 and 21 engage the hinge member 8 and swing the

dogs outwardly until the hook portions 22 and 23 engage the hinge member. The fall rope is then hauled in, the upward pull through the sheaves upon the upper ends of 5 the two lever arms causes them to pivot about the hinge member 8 due to the engagement of the dogs therewith and thus causes the bucket members to be swung toward each other and to dig into the material. This action is facilitated by the 10 downward thrust transmitted from the sheave 11 through the arms 12 and 13.

When the bucket reaches the fully closed 15 position, the parts are in the relation shown in Figure 1. The bucket is now supported from the hinge member 8 resting upon the two dogs 20 and 21. The fall rope is hauled in until the bucket is lifted to the conveying 20 level and here in this position, the fall rope passes smoothly to the sheaves for the traction movement.

When the bucket reaches the discharge 25 position, the fall rope is payed out so as to allow a small amount of slack after the bucket rests upon the ground or upon the pile of material. This slack permits the lever arms 14 and 15 to fall slightly toward the hinge member 8, and the pivots of the dogs 20 and 21 are then in this closed position 30 so related to the hinge member that the dogs are swung by gravity clear of the hinge member. The weight of the bucket members themselves and of the material thereon then quickly causes the members to move to the position of Figure 2, discharging 35 the material in the bucket. This completes the cycle of operation.

It will be observed that my bucket is 40 simple in design and construction and composed of relatively few parts and that it is simple in operation. In the closing or digging movement, full leverage is had. In the tractioning movement, either open or closed, the rope passes the sheaves with the 45 minimum possible resistance.

The particular embodiment shown is by way of example only and it is my intention to cover all modifications coming within the spirit and scope of the following claims.

50 I claim:

1. In a clam-shell bucket, a pair of coacting bucket members hingedly connected together, a lever arm connected to each bucket member, and means carried by the lever arms adapted to detachably engage the bucket above its center of gravity whereby when supported by said means, the bucket is closed by gravity, said means being adapted to disengage the bucket to permit the bucket to open when the weight of the bucket is taken from said means.

60 2. In a clam-shell bucket, a pair of coacting bucket members hingedly connected together, a lever arm connected to each bucket member, and dogs carried by the lever arms

and adapted to engage the bucket hinge member to support the bucket thereon, said dogs being adapted to disengage from the hinge member when, in the closed position, the weight of the bucket is removed from 70 the hinge.

3. In a clam-shell bucket, a pair of coacting bucket members hingedly connected together, a lever arm connected to each bucket member adjacent its outer, upper edge, the lever arms crossing each other and being provided at intermediate points with dogs 75 adapted to engage the bucket hinge member, and at their free ends with sheaves adapted to receive a conveyor fall rope, the conveyor fall rope serving to move the levers relative to the bucket when the bucket is disengaged from said dogs.

4. In a clam-shell bucket, a pair of coacting bucket members hingedly connected together, a lever arm connected to each bucket member adjacent its outer, upper edge, the lever arms crossing each other and being provided at intermediate points with dogs 80 adapted to engage the bucket hinge member, and at their free ends with sheaves adapted to receive a conveyor fall rope, the bucket 85 being supported from the sheaves by the levers when the dogs are disengaged from the hinge member.

5. In a clam-shell bucket, a pair of coacting bucket members hingedly connected together, a lever arm connected to each bucket member adjacent its outer, upper edge, the lever arms crossing each other and being provided at intermediate points with dogs 90 adapted to engage the bucket hinge member, and at their free ends with sheaves adapted to receive a conveyor fall rope, the sheaves 95 and levers being so constructed that the sheaves and free ends of the levers are located adjacent each other when the bucket is supported from the sheaves.

6. In a clam-shell bucket, a pair of coacting bucket members hingedly connected together, a lever arm connected to each bucket member adjacent its outer, upper edge, the lever arms crossing each other and being provided at intermediate points with dogs 100 adapted to engage the bucket hinge member, and at their free ends with sheaves adapted to receive a conveyor fall rope, and an additional sheave supported from the bucket members by arms, said sheaves 105 being adapted to receive the fall rope upon its upper portion.

7. In a clam-shell bucket, a pair of coacting bucket members hingedly connected together, a lever arm connected to each bucket member adjacent its outer, upper edge, the lever arms crossing each other and being provided at intermediate points with dogs 110 adapted to engage the bucket hinge member, and at their free ends with sheaves 115 adapted to receive conveyor fall rope, pull 120 the bucket members apart to open the bucket, and the weight of the bucket being supported from the sheaves.

upon the fall rope serving to draw the sheaves together.

8. In a clam-shell bucket, a pair of coacting bucket members hingedly connected together, a lever arm connected to each bucket member adjacent its outer, upper edge, the lever arms crossing each other and being provided at intermediate points with dogs adapted to engage the bucket hinge member, and at their free ends with sheaves adapted to receive a conveyor fall rope, and an additional sheave supported from the bucket members by arms, said sheave being adapted to receive the fall rope upon its upper portion, the sheaves carried by the lever arms being below and upon either side of the additional sheaves when the levers are moved to permit the dogs to engage the hinge member.
9. In a clam-shell bucket, a pair of coacting bucket members hingedly connected together, a lever arm connected to each bucket member adjacent its outer, upper edge, the lever arms crossing each other and being provided at intermediate points with dogs adapted to engage the bucket hinge member, and at their free ends with sheaves adapted to receive a conveyor fall rope, and an additional sheave supported from the bucket members by arms, said sheave being adapted to receive the fall rope upon its upper portion, the arms being so related to the bucket members, thrust transmitted to the additional sheave by the fall rope serving to swing the bucket members to closed position.

10. In a clam-shell bucket, a pair of co-

acting bucket members hingedly connected together, a lever arm connected to each bucket member adjacent its outer, upper edge, the lever arms crossing each other and being provided at intermediate points with dogs adapted to engage the bucket hinge member, and at their free ends with sheaves adapted to receive a conveyor fall rope, and an additional sheave supported from the bucket members by arms, said sheave being adapted to receive the fall rope upon its upper portion, the parts being so related that the lever arm sheaves are adjacent each other and above the additional sheave when the bucket is in closed position.

11. In a clam-shell bucket, a pair of coacting bucket members hingedly connected together, a lever arm connected to each bucket member adjacent its outer, upper edge, the lever arms crossing each other and being provided at intermediate points with dogs adapted to engage the bucket hinge member, and at their free ends with sheaves adapted to receive a conveyor fall rope, and an additional sheave supported from the bucket members by arms, said sheave being adapted to receive the fall rope upon its upper portion, the parts being so related that the lever arm sheaves are adjacent each other and above the additional sheave when the bucket is in closed position, and all parts of the bucket lie below the lever arm sheaves.

Signed at Elkhart, Indiana, this 12th day of August, 1922.

DANIEL E. STAIR.
